JOHN YOUNG OF C, OF FAIR VIEW, AND C. I. GRUMBINE, OF FREDERICK, MARYLAND.

Letters Patent No. 90,622, dated May 25, 1869.

IMPROVEMENT IN MACHINE FOR BORING POSTS AND POINTING RAILS.

The Schedule referred to in these Letters Patent and making part of the same.

To all whom it may concern:

Be it known that we, JOHN YOUNG OF C, of Fair View, in the county of Frederick, and State of Maryland, and C. I. GRUMBINE, of the city and county of Frederick, and State of Maryland, have invented a new and improved Machine for Boring Posts and Pointing Rails; and we do hereby declare that the following is a full, clear, and exact description of the construction and operation of the same, reference being had to the accompanying drawings, making a part of this specification, in which—

Figure 1 is a vertical section through the line $z z$ of fig. 2.

Figure 2 is a top view.

Figure 3 is a detached view, showing the construction of the knives.

This invention relates to the machine patented by John Young of C, July 10, A. D. 1855, No. 13,243, and consists in making the augers employed in that machine adjustable, to adapt them to crooked as well as straight posts, in providing two rotary knives, of peculiar construction, to sharpen the rails, and in the novel construction of the device which operates the clamps that hold the rail, whereby it is more easily and effectively managed than in the old machine.

In the drawings—

F indicates the main frame, that supports the knives K K, and their platform, or frame E, together with the clamps C, and their sliding platform, or frame D, the carriage G, that carries head-blocks H H, and a circular saw, S, that may be employed in connection with said carriage, when the knives and their frame are removed, for the purpose of sawing out posts, rails, pickets, laths, and other small lumber or timber.

In connection with this main frame is a small side-frame, B, attached to it, and supporting the augers A A.

Having thus described the frame, and the general arrangement of the parts, we will now proceed to describe the construction and operation of the several improvements which form the subject of this application, the construction of the other parts of the machine being substantially the same as that of the apparatus heretofore patented by John Young of C.

I I' I² are three metallic brackets, or knees, fixed to the frame B, in line, and supporting a vertically-adjustable metallic frame, J, which can be fixed higher or lower, by means of slots and set-screws i i, and the function of which is to support the augers and their driving-shaft M, and wheel N, and, by being adjusted up and down, to bring the augers to bear upon the post at the right point, however crooked it may be.

The shaft M is provided with a grooved cylinder, or elongated cog-wheel, m, which gears with smaller cog-wheels, a a', attached to the augers, and thereby enables the latter to be slid back and forth longitudinally,

or "fed to" and withdrawn from the post, without getting out of gear.

A lever, L, is provided, by which both augers can be simultaneously moved back and forth for such purpose, the auger-frame J being adjustable in height, for the purpose above specified, by means of a lever, J'.

The clamp C is, as in the old machine, a box, with one side and the bottom fixed, and the other side adjustable toward or from the former, for the purpose of clamping and holding the post, rail, or other article, firmly in position while the machine is operating upon it.

The improvement which we have made to this part of the device consists in providing a vertical projection upon the upper edge of each side of said box, (shown at e e,) in connection therewith, an arm, or block, O, articulated to the top of the standard, on the fixed side, and capable of bending down over and embracing between its bifurcated, or slotted opposite end the standard, or projection of the movable side of the box, and, together with these parts, an eccentric-headed lever, P, pivoted, or jointed to the end of the bifurcated block; a ratchet-plate, R, fixed to the block, in the form of a segment of a circle, having its centre at the pivot o, of the lever P; and a pawl, p, attached to the lever, and operating in connection with the ratchet-plate.

The eccentric head of the lever operates against the side of the movable wall of the box, or against the standard 2, fixed thereto, and, when the lever is brought to a horizontal position, forces such side inward against the rail or post, (shown by the red lines,) thereby clamping the former firmly.

When the lever-handle is raised, the parts do not double up at the pivot o, but the pawl on the lever engages with the ratchet-plate attached to the arm, or block O, and thereby the latter is raised at the same time with the lever, and the rail or post is at once liberated from the clamp.

The apparatus is very simple and effective, and not liable to get out of order by frequent use.

The clamping-box C is pivoted to the sliding platform D, so as to be turned to any position.

The platform D enables the box to be adjusted toward one side or the other of the frame F, and the carriage G, which slides longitudinally with the frame F, enables the clamping-apparatus to be arranged at any required distance from the augers, saw, or knives, or to be removed from the machine entirely, if desired.

The circular rotary knives K K' are, by their construction, adapted to the sharpening of fence-rails. They, with their driving-shaft Q, and its belt-pulley q or crank q', are mounted upon the main frame, by means of a frame, or platform E, which can be detached and removed by withdrawing the form-bolts t t.

The knives consist of two concavo-convex disks, arranged upon the shaft, with their convex sides toward each other, as shown in figs. 2 and 3, and capable of being adjusted at any suitable distance apart.

Each knife, or disk is provided with a curved oblique slot, and attached therein by means of slots and set-screws *o*, so as to be adjustable, one or more curved cutting-blades, *T T*, the edges of which project slightly from the inner face of the disk, as seen in fig. 3.

The saw *S* may be run by a belt from pulley *q*, and the driving-shaft *M*, of the augers, may receive motion from the same source, by means of a suitable pulley, on its outer end, below the augers.

The operation of the machine will probably have been already fully understood from the above description.

When about to bore posts, the frame *E*, with its knives, may be removed from the machine, and the post placed on the carriage *G*, and fastened by means of the head-blocks *H H*. The augers are then adjusted, and the post bored.

To sharpen rails, put the frame *E* and its connected apparatus in place. Put the rail properly in the clamp, and fasten it there, by bringing the lever down, and apply the end of the rail to the knives, by moving the carriage up.

To saw posts, &c., remove the frame *E* and its ap-

paratus, and set the saw *S* in motion, feeding the lumber thereto by means of the carriage *G'*. The parts *D*, *C*, &c., and the platform upon which they rest, may be detachable and removable from the carriage, if it should be found more convenient for sawing.

Having thus described our invention,

What we claim as new, and desire to secure by Letters Patent, is—

1. In combination with the slotted metallic brackets *I I' I'*, set-nuts and screws *i i* and lever *J'*, the vertically-adjustable frame *J*, carrying the boxes for the auger-mandrels, and shaft *M*, all constructed as shown and described, for the purpose specified.

2. The combination of the eccentric-headed lever *P*, pawl *p*, ratchet-plate *R*, block *O*, and clamping-box *C*, when the several parts are constructed to operate in the manner and for the purpose specified.

3. The machine herein described, for boring posts and sharpening rails, consisting essentially of the disks *K K'*, carrying the curved adjustable cutting-blades *T T*, the carriage *G*, and the clamping-box *C*, and its appendages, all constructed and arranged to operate in the manner and for the purpose specified.

JOHN YOUNG OF C.
C. I. GRUMBINE.
